UNITED STATES PATENT OFFICE

168,320

COMBINED PACKING AND DISPLAY CASE FOR LIPSTICKS

Maurice L. Shanahan, Los Angeles, Calif.

Application September 10, 1951, Serial No. 16,590

Term of patent 14 years

(Cl. D80—11)

To all whom it may concern:

Be it known that I, Maurice L. Shanahan, a citizen of the United States, residing at Los Angeles, in the county of Los Angeles, and State of California, have invented a new, original, and ornamental Design for a Combined Packing and Display Case for Lipsticks, of which the following is a specification, reference being made to the accompanying drawing, forming a part thereof:

I claim:

The ornamental design for a combined packing and display case for lipsticks, as shown.

MAURICE L. SHANAHAN.
